US00D852201S

(12) **United States Design Patent** (10) Patent No.: **US D852,201 S**
Chan et al. (45) Date of Patent: ** Jun. 25, 2019

(54) **CASE FOR PORTABLE ELECTRONIC COMPUTING DEVICE**

(71) Applicant: **Pioneer Square Brands, Inc.**, Seattle, WA (US)

(72) Inventors: **Jaimie Emerald Chan**, Renton, WA (US); **Michael Cooper Ferren**, Camus, WA (US); **Michael Heecheol Kim**, Seattle, WA (US)

(73) Assignee: **PIONEER SQUARE BRANDS, INC.**, McLean, VA (US)

(**) Term: **15 Years**

(21) Appl. No.: **29/676,536**

(22) Filed: **Jan. 11, 2019**

(51) LOC (11) Cl. **14-02**

(52) U.S. Cl.

USPC **D14/440**

(58) **Field of Classification Search**

USPC D14/440, 447, 250; 206/45.23, 320, 206/45.2; 361/679.55; 294/25; 224/218

CPC ... G06F 1/1628; G06F 1/1626; A47B 23/044; H04B 1/3888

(57) **CLAIM**

The ornamental design for a case for portable electronic computing device, as shown and described.

DESCRIPTION

FIG. 1 is a front perspective view of a first embodiment.

FIG. 2 is a front elevational view thereof.

FIG. 3 is a rear elevational view thereof.

FIG. 4 is a top elevational view thereof.

FIG. 5 is a bottom elevational view thereof.

FIG. 6 is a left elevational view thereof; and,

FIG. 7 is a right elevational view thereof.

The features shown in broken lines in the drawing figures depict features that form no part of the claimed design.

1 Claim, 3 Drawing Sheets
